Primary Examiner — Jonathan J Han*Assistant Examiner* — Molly K. Orzechowski(74) Attorney, Agent, or Firm — Lerner David LLP(57) CLAIM

The ornamental design for a footwear, as shown and described.

DESCRIPTION

FIG. 1 is a front bottom left perspective view of a footwear, according to my new design.

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear bottom right perspective view thereof.

The broken lines of even length depict portions of the footwear that form no part of the claimed design. The broken lines of uneven length are boundary lines that form no part of the claimed design.

1 Claim, 8 Drawing Sheets(56)
